Patented Feb. 4, 1919.

UNITED STATES PATENT OFFICE.

OLIVER J. SMITH, OF MONROE, LOUISIANA.

ASH-PAN.

1,293,223.

Specification of Letters Patent.

Patented Feb. 4, 1919.

Application filed July 3, 1917. Serial No. 178,456.

To all whom it may concern:

Be it known that I, OLIVER J. SMITH, a citizen of the United States of America, and resident of Monroe, in the parish of Ouachita and State of Louisiana, have invented certain new and useful Improvements in Ash-Pans, of which the following is a specification.

This invention relates to steam boilers and furnaces and particularly to locomotive furnaces, the said invention being directed more particularly to ash pans for locomotives.

An object of this invention is to provide an ash pan which can be readily attached to or removed from locomotives now in common use, the said invention having for its further object the provision of novel means for maintaining or augmenting the supply 20 of air under the grate or grate bars, means being also provided for regulating the said supply of air.

A further object of this invention is to provide an ash pan in which the ashes will gravitate toward the discharge opening thereby facilitating the blowing out of the said ashes or the removal of the same from the said ash pan.

A still further object of this invention is to provide ventilators which can control the point at which air is delivered under the fire bed with respect to the front or back thereof.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a view in elevation of a fragment of the exterior of a boiler furnace with the invention applied thereto;

Fig. 2 illustrates a plan view partly in section of the ash pan detached;

Fig. 3 illustrates a sectional view on a line 50 corresponding with the line 3—3 of Fig. 2; and

Fig. 4 illustrates a front view of a fragment of the ash pan.

In these drawings 5 denotes the locomotive fire box of a conventional type having the ash pan applied thereto, the said ash pan

comprising inwardly curved sides 6 supported from the fire box by means of the hangers 7, although any appropriate means may be supplied for connecting these parts 60 together. The sides have openings 6^a therein with which chutes to be hereinafter described communicate.

The sides are tapered in width from back to front and the bottom 8 of the ash pan has 65 upturned flanges 8^a connected to the sides by fastenings 9, such as rivets or the like, and the said flanges are tapered in width from the back to front, so that the bottom is supported in an inclined position from 70 front to back, thus causing the ashes in the pan to gravitate toward the back and facilitating the discharge of the said ashes when they are blown out under the usual process for discharging ashes.

The back of the ash pan is closed or guarded by a door 10 mounted on hinges, such as 11 and any suitable means may be supplied for holding the door closed.

At points intermediate the length of the 80 sides of the ash pan ventilators are introduced, the said ventilators comprising hoods or chutes 12 which communicate with the interior of the fire box through the openings 6^a in said sides. The outer ends of these 85 hoods are open and face the direction of travel of the locomotive so that air may be collected as the locomotive is traveling. The mouths or outer ends 13 of the chutes are preferably flared so that a greater volume 90 of air is collected and forced into the fire box.

For convenience of illustration, two of the air collectors are shown on each side, although these may be modified as to size 95 and configuration within predetermined bounds without departing from the spirit of the invention.

Each of the ventilators is preferably supplied with a damper comprising a closure 100 14 and a rod 15 journaled in the sides of the ventilator and the outer end of the said rod has an operating crank 16 on it so that any suitable means may be provided for rotating the rod and operating the valve or 105 damper controlling the supply of air to the fire box.

By reason of the construction, it has been found that air may be delivered uniformly to the under surface of a fire bed and that 110 owing to the velocity of the air traveling therein, a forced draft is effected which to a

great extent when the locomotive is in motion, supplies sufficient draft without the use of a blower or other force draft mechanism.

5. The construction of the device is comparatively inexpensive and by reason of the simple manner of attachment it can be placed on locomotives now in common use without materially increasing the cost.

10. I claim—
In an ash pan for locomotives, sides having openings therein, chutes extending to the sides in communication with the said

openings, said chutes having openings facing the direction of travel of the locomotive, a bottom for the ash pan having side flanges connected to the said sides, the said flanges and said sides being tapered in width from the back to front whereby the bottom of the pan is on an incline, a door for closing the ash pan, and a damper in each of the said chutes, said damper comprising a rod journaled in the side of the chute and a closure carried by the said rod.

OLIVER J. SMITH.
